GOLF CAR

John A. Gale, Wayzata, Minn., assignor to Toro Manufacturing Corporation, Minneapolis, Minn., a corporation of Minnesota

Filed Feb. 5, 1965, Ser. No. 83,696

Term of patent 14 years

(Cl. D14—3)

Fig. 1

Fig. 2

Fig. 3

The dominant features of my design reside in the portions shown in full lines.

I claim:

The ornamental design for a golf car, as shown and described.
